(57) **CLAIM**

I claim the ornamental design for a flashlight head, as shown and described.

DESCRIPTION

FIG. 1 is a perspective view of a flashlight head.

FIG. 2 is a top view of the flashlight head as illustrated in FIG. 1.

FIG. 3 is a left side elevation view of the flashlight head as illustrated in FIG. 1.

FIG. 4 is a rear elevation view of the flashlight head as illustrated in FIG. 1.

FIG. 5 is a right side elevation view of the flashlight head as illustrated in FIG. 1.

FIG. 6 is a front view of the flashlight head as illustrated in FIG. 1.

FIG. 7 is a rear view of the flashlight head as illustrated in FIG. 1.

FIG. 8 is a perspective view of the flashlight head showing the legs of the tripod in an open position; and,

FIG. 9 is another alternative perspective view of the flashlight head device showing the legs of the tripod in an open position. The dashed lines in various figures are for illustrative purposes only and form no part of the claimed design.
